UNITED STATES PATENT OFFICE.

WILLIAM I. SKINNER, OF RICHLFIELD, NEW YORK.

POTATO-DIGGER.

SPECIFICATION forming part of Letters Patent No. 738,951, dated September 15, 1903.

Application filed November 18, 1899. Serial No. 737,421. (No model.)

To all whom it may concern:

Be it known that I, WILLIAM I. SKINNER, a citizen of the United States of America, and a resident of the town of Richfield, Otsego county, New York, (whose post-office address is Chepachet, Herkimer county, New York,) have invented certain new and useful Improvements in Potato-Diggers, of which the following is a specification.

1c The invention relates to an improvement in potato-diggers, particularly a power-operated machine to dig and separate the potatoes from the soil, leaving the potatoes exposed on the surface in a readily-accessible position.

15 The invention consists in the details of construction hereinafter described in connection with the accompanying drawings, wherein—

Figure 1 is a perspective view of a potato-digger constructed in accordance with my invention. Fig. 2 is a plan view of the same. Fig. 3 is a side elevation of the machine. Figs. 4 and 5 are details of the lever mechanisms.

The machine, preferably of suitable type for draft purposes, is mounted upon driving-

25 wheels 1, suitably ribbed to prevent slipping, the spokes 2 of which are preferably cast sinuous to provide for expansion and contraction. The wheels 1 are loosely mounted upon an axle 3, suitable ratchet mechanism

30 of any well-known or preferred type—such, for example, as illustrated in dotted lines in Fig. 3—being arranged to cause operative engagement of the wheels and axle when the machine is moving forward and permit the

35 disengagement of these parts when the machine is moved rearwardly, the object and necessity of such arrangement being well understood in machines of the character of my invention and requiring no detailed description.

40 The main frame 4, of angle steel and substantially U-shaped, is mounted upon the axle 3, being provided with suitable axle-receiving boxes 5. The front rail of frame 4 rests contiguous to the rear end of the draft-

45 tongue 6 of the machine, being adjustably connected thereto through the medium of a lever 7, pivoted to the main frame and suitably held when in proper position by the usual dog and notched segment 8. An angle-arm 9, secured to the lower end of lever 7, is formed

at its free end with a slot 10, to receive a pin projecting from the tongue.

11 represents an adjustable frame pivoted in bosses 12, rising from the main frame 4. The adjustable frame is made movable with relation to the main frame through the medium of a transverse shaft 13, suitably mounted on the main frame 4 and provided with fixed arms 14, each carrying a link 15, pivoted to the adjustable frame. A lever 16, adjustably held by the usual dog and notched segment 17, is secured to shaft 13 and serves to operate the latter to adjust the frame 13 in an obvious manner.

65 The plow or digging-shovel 18, with its rear side portions turned up, as at 19, is supported by standards 20, secured to the upturned parts 19 and to the adjustable frame 11 and is braced and supported by braces 21, extending from standards 20 to the frame 11. The shovel is substantially V-shaped and ordinarily depressed, so that the pointed end will enter the ground beneath the potatoes therein.

70 Immediately in rear of the shovel is located the shaker-head 22, in which is secured a series of shaker-fingers 23, preferably in steel wire bent in U shape to form two integral fingers and held in a longitudinal recess in the shaker-head by bolts or rivets. A rapid reciprocating motion is imparted to the shaker-head and fingers by pitmen 24, secured to the head and pivoted in the eccentrics 25, mounted on a shaft 26, pivoted on the adjustable frame 11. Motion is imparted to shaft 26 through 75 a sprocket 27, secured on the shaft, connected by a link belt 28 to a sprocket 29, mounted on a shaft 30, journaled in adjustable frame 11. A small sprocket 31 is also fixed on shaft 30 and is driven from a sprocket 32 on axle 90 80 3 by link belt 33. Idlers 34 and 35, mounted in brackets 36, fixed to frame 11, permit the accommodation of the link belt 28 and 33 to the adjustment of frame 11.

To render more effective the reciprocation 95 of the shaker-fingers, I provide means for increasing the aforesaid movement, such means comprising a bow spring-plate 37, arranged transversely on the rear bar of adjustable frame 11, being centrally secured to the frame, with its upwardly-projecting free ends secured by flexible connections, such as chains

38, to the ends of the shaker-head 22. The reciprocation of the shaker-head through mechanism hereinbefore described causes intermittent tension on the free ends of spring-plate 37 in an obvious manner, hence increasing materially the shaking and rocking motion of the fingers 23 and increasing their efficiency.

39 represents cutters vertically arranged

10 within the plane of wheels 1 and rigidly secured at their upper ends to the adjustable frame 11, as shown. The cutters are suitably braced by rods 40, fixed thereto and extending to the upturned sides 19 of the shovel 18.

15 The cutters are designed to cut vines, weeds, and sod in advance of the shovel.

The shaker-head is supported by links 41, secured to the end portions of the head forwardly and upwardly, with curved portions 20 extending over axle 3, the forward ends being connected to the adjustable frame 11. It will be noted that links 41 form a support for the shaker-head and that such is in the nature of a spring-support, owing to the length and

25 inclination of the links. Hence the direct vertical movement of the shaker-head otherwise resulting from the operation of the pit-man 24 is interrupted by the link-support and converted thereby into a jogging or vibrating

30 movement. As this movement is exerted against the tension of spring-plate 37, it follows that such tension will act to increase the reciprocation, rendering the movement of the fingers much more effective than the ordinary vertical reciprocation incident to prior

35 structures of this class.

The driver's seat 42, supported from the draft-tongue, is arranged about over axle 3 to enable the driver to use his weight to balance

40 the machine. Levers 7 and 16 are arranged to be conveniently operated by the driver on seat 42.

The operation of the machine is apparent from the above-detailed description read in 45 connection with the drawings, it being understood that the shovel passes beneath the potatoes in the ground, being adjusted at an angle, and that earth and potatoes are forced rearward on the shovel and guided between the

50 upturned ends 19 onto the shaker-fingers 23, in the reciprocation of which the potatoes are separated from the earth and finally forced off the free ends of the fingers to lie exposed on the ground, when they may be readily

55 gathered. The operation of the spring-plate 37, tending to increase the reciprocatory movement of the shaker-fingers, acts to materially assist in the separation of potatoes and earth, thereby preventing the clogging of material

60 on the fingers, which is an objectionable feature incident to other machines of this character.

It will be noted that the shovel, shaker-fingers, and other operative parts are supported solely from an adjustable frame and 65 that their position may be varied as desirable by the single adjustment of this frame. Hence

the angle of the shovel may be varied, its cutting depth may be altered, or the entire mechanism may be lifted from operative position by the single adjustment of the frame 11 7c in the desired direction. The adjustment of the main frame with relation to the draft-tongue also permits ready variation of the angle of the shaker-fingers and shovel with relation to the ground. 75

It is evident that various changes may be made in the constructions and arrangements of parts described without departing from the spirit of my invention, and I wish it understood that I do not limit myself to the exact 80 details described.

What I claim is—

1. In a potato-digger, a main frame, an adjustable frame pivoted thereto, a shovel, shaker-fingers, means for reciprocating said 85 fingers, and cutters located in advance of the shovel, all supported solely by and adjustable with said adjustable frame.

2. A potato-digger comprising a frame, a shovel, supported thereby, shaker-fingers in 90 rear of the shovel, mechanism for reciprocating said fingers, and means independent of said reciprocating mechanism for vibrating the fingers.

3. A potato-digger comprising a frame, a 95 shovel supported thereby, shaker-fingers in rear of the shovel mechanism for reciprocating said fingers, and spring connections independent of said reciprocating mechanism for vibrating the fingers.

4. A potato-digger comprising a frame, a shovel supported thereby, shaker-fingers in rear of the shovel, means for reciprocating said fingers, a spring-plate secured on the frame, and connections between the spring- 105 plate and shaker-fingers.

5. A potato-digger comprising a main frame, an adjustable frame pivoted thereto, a shovel supported by the adjustable frame, shaker-fingers supported by the adjustable 110 frame in rear of the shovel, means carried by the adjustable frame to reciprocate the fingers, and spring connections between the fingers and adjustable frame, as and for the purposes stated. 115

6. A potato-digger comprising a wheeled frame, an adjustable frame pivoted thereto, a shovel supported by the latter frame, a shaker-head yieldingly supported from the adjustable frame, fingers secured in said head, 120 and means carried by the adjustable frame to reciprocate said head and fingers.

7. A potato-digger comprising a wheeled frame, an adjustable frame pivoted thereto, a shovel supported by the latter frame, a shaker-head yieldingly supported from the adjustable frame, fingers secured in said head, 125 means carried by the adjustable frame to reciprocate said head and fingers, and a spring connection between the adjustable frame and shaker-head. 130

8. A potato-digger comprising a frame, a

shovel supported thereby, shaker-fingers adapted for reciprocation from the frame, a bow spring-plate secured to the frame, and connections between the said spring-plate and shaker-fingers.

9. In a potato-digger, a main frame, an adjustable frame pivoted thereto, a vibrating separator, means for reciprocating said separator, and links secured to said adjustable frame and inclined therefrom and secured to said separator.

10. In a potato-digger, a main frame, an auxiliary frame adjustably secured thereto, a shaker head and fingers, inclined links forming the support for said shaker-head and connected to the adjustable frame, and means

to reciprocate said shaker-head against the resistance of said links.

11. In a potato-digger, a main frame, an auxiliary frame adjustably secured thereto, a plow carried by the auxiliary frame, a shaker-head yieldingly supported from said auxiliary frame, and means for reciprocating said shaker-head, said means being carried by the auxiliary frame and being independent of the yielding support for said shaker-head.

Signed by me at Richfield Springs, New York, this 8th day of November, 1899.

WILLIAM I. SKINNER.
